UNITED STATES PATENT OFFICE.

CHARLES D. CAREY, OF CHEYENNE, WYOMING.

POLO BRIDLE.

Application filed October 6, 1925. Serial No. 60,778.

To all whom it may concern:

Be it known that I, CHARLES D. CAREY, a citizen of the United States, residing at Cheyenne, in the county of Laramie and State of Wyoming, have invented certain new and useful Improvements in Polo Bridles; and I do declare the following to be a full, clear, and exact description of the invention, such as will enable others skilled in the art to which it appertains to make and use the same, reference being had to the accompanying drawings, and to the characters of reference marked thereon, which form a part of this application.

15 This invention relates to improvements in polo bridles, more particularly the cavesson nose band. It is the object of the invention to produce a bridle of such construction as to make it possible to change bits quickly without necessitating the removing of the whole bridle or removing the standing martingale which is used on most polo ponies.

20 The above and other objects that will become apparent as the description proceeds are attained by a construction that I will now proceed to describe in detail, reference for this purpose being had to the accompanying drawing in which the invention has been illustrated and in which:

25 Fig. 1 is a side view of a horse's head showing the completed bridle in place;

30 Fig. 2 shows the halter portion that remains after the bit has been removed,

35 Fig. 3 shows a perspective view of the improved bridle, and

40 Fig. 4 is a view showing the manner of connecting the bridle with the martingale.

When playing polo, it is often necessary to change bits because of one being too severe or not severe enough. The standing martingale has to be unbuckled and the whole bridle removed. When changing bridles, the pony is liable to get away before another bridle can be put on him. In order to prevent the horses from getting away, I have produced a bridle that is associated with a halter which is not required to be removed from the horse's head or removed from the standing martingale M and which is so constructed that it cooperates with other parts to form a bridle.

In the drawing the construction has been clearly shown and comprises a crown piece 1 which is split from each end up to the point 2 so as to form a throat latch 3 and

a wider cheek strap 4 and 4^a. A brow band 5 has its ends formed into loops 6 through which the crown piece 1 passes, the throat latch 3^a on the off side is longer than the corresponding strap 3 on the near side and 60 is provided with a buckle which cooperates with holes 7 in the latter. A nose band 8 has one end provided with a buckle 9 that cooperates with openings in the end 10 for the purpose of adjustment in the manner 65 shown. Short cheek straps 11 and 11^a are secured to the nose band at points 12 and 12^a and extend upwardly. Their upper ends have buckles 13 that cooperate with holes in straps 4 and 4^a. The assembly just described forms a halter such as has been illustrated in Fig. 2. This halter is so constructed that it forms the bases for the bridle with which it cooperates and which is constructed as follows: a long strap 15 70 has the end on the off side buckled or sewed to the bit 16 in the manner indicated by numeral 17. This strap is passed through the loop 6 on the off side, thence over the crown strap 1 and downwardly through the 75 loop 6 on the near side where it cooperates with the buckle 18 that is attached to the upper end of the short cheek strap 19 whose lower end is buckled to the bit as indicated at 20. The completed assembly, which is 80 shown in perspective in Fig. 3, constitutes the bridle and is applied to the horse in the manner shown in Fig. 1. The loops 6 and the halter serve to hold the strap 15 from sliding forwardly over the 85 horse's ears. If it is desired to change the bits or to remove the bit entirely, this may be done by disconnecting the strap 15 from the buckle 18 and withdrawing the strap 15 from the loops 6. It is evident that 90 this can be done without removing the halter part of the bridle so that there is no chance of the horse getting away. The long and short cheek straps 15 and 19 are attached to whatever bit is wanted and the long cheek 95 strap is slipped through the brow band loops over the crown and buckled into the short cheek strap 19 on the near side, making the change complete. When the bridle is constructed in the manner described, there will 100 always be a smooth surface against the crown of the horse's head as the strap 15 rests upon the crown piece. The bit supporting portion is also readily accessible for ease in removal and in applying.

Having now described the invention what I claim as new is:

A polo bridle comprising, in combination, a halter portion, and a bit supporting portion, the halter comprising a crown piece adapted to pass over the horse's head, a brow band having its ends formed into loops, a nose band, cheek straps secured to the nose band, means for securing the cheek straps to the crown piece, a throat latch, a bit, a long cheek strap secured to one end of said bit, a short cheek strap secured to the other end of said bit, said long strap be-

ing adapted to pass through one of the loops in the ends of the brow band, thence 15 over the crown piece and downwardly through the loop on the other side, and means comprising a buckle for securing the free end of the long cheek strap to the free end of the short cheek strap whereby the 20 bit supporting part may be removed and replaced without disturbing the halter portion.

In testimony whereof I affix my signature.

CHARLES D. CAREY.
